UNITED STATES PATENT OFFICE.

JAMES W. KELLY, OF CHICAGO, ILLINOIS.

WATER-CLOSET.

No. 905,589.

Specification of Letters Patent.

Patented Dec. 1, 1908.

Application filed September 19, 1907. Serial No. 393,636.

To all whom it may concern:

Be it known that I, JAMES W. KELLY, a citizen of the United States, residing at Chicago, in the county of Cook and State of Illinois, have invented a new and useful Improvement in Water-Closets, of which the following is a specification.

My invention relates particularly to water-closets for public use, as, for instance, in school-buildings or in analogous situations.

My primary object is to provide an improved construction enabling a plurality of closet-bowls to be applied directly to a single soil-pipe in such manner as to obviate the necessity of using long branch-pipes in situations where but little inclination of the same is possible, thereby further obviating the necessity for re-vent pipes for the traps of the several closet-bowls, and, also, avoiding siphonage from the traps of closets not in use upon the flushing of a closet in use.

A further object is to provide a simple, inexpensive and effective construction for the closet-compartments.

The invention is illustrated in its preferred embodiment in the accompanying drawings, in which—

Figure 1 represents a broken vertical section of a group of closets, soil-pipe and closet-bowls constructed and arranged in accordance with my invention, the section being taken as indicated at line 1 of Fig. 3; Fig. 2, a broken horizontal sectional view, showing the manner of connecting the walls of the closet-compartments with the soil-pipe; Fig. 3, a similar sectional view, taken as indicated at line 3 of Fig. 1 and showing all of the compartment walls in place; and Fig. 4, a perspective view of a tank-bracket employed.

In the construction illustrated, A, A¹ represent aligned vertical soil-pipe sections; A², an interposed soil-pipe fitting; B, closet-bowls grouped about the soil-pipe and connected with the branches of the fitting A²; C, C, a series of closet-compartment walls radiating from the soil-pipe section A, upon which they are supported, and forming compartments C¹; and D, tanks (one shown) supported between the walls C and connected with the bowls B.

The fitting A² comprises a horizontally disposed hollow circular body a having a plurality of pipes a¹ radiating from its circumference, and vertical pipe-sections a², a³ connected with the central portions of the

upper and lower walls of said hollow body. The fitting and its pipe connections are preferably formed integrally with each other by casting. The pipes a¹ have upturned extremities with flanges a⁴ for receiving the bowls. The pipe-section a² is provided with a bell-mouth for receiving the lower flanged end of the pipe-section A; and the pipe-section a³ has a flanged extremity which fits within the bell-shaped upper end of the pipe-section A¹. The lower wall of the hollow body a is dished, so that at any radial section therethrough the bottom wall slopes centerward, i. e., toward the pipe-section a³.

The bowls B may be of any approved construction. The walls C may be of marble, slate or galvanized sheet steel. They are spaced apart and connected by V-shaped bars c which are secured to the upper and lower margins thereof by bolts, or rivets, c¹, which pass through the slab and the adjacent wings of the V-shaped irons. The inner vertical edges of the slabs, or partitions, C, abut against the central pipe-section A, and the slabs and irons are so proportioned with relation to the pipe that when all are properly connected the whole structure will be tightly clamped upon and supported by the pipe-section, it being observed that the apexes of the V-shaped irons are fashioned to abut against and conform to the pipe-section. The slabs may be temporarily supported in any suitable manner while the irons are being connected. If desired, the irons may be fashioned to allow small spaces between their base portions and the slabs, as shown in Fig. 2, so that when the innermost bolts, or rivets, are tightened the clamping upon the pipe will be effected. The tanks D are supported by brackets d whose vertical arms d¹ are riveted or otherwise secured to the slabs.

The construction described is simple, inexpensive, and thoroughly sanitary. There being no long conduits leading from the bowls, the expense incident to separate re-venting means for the several closet-traps is obviated. It will be understood that a fitting A² may be connected with the soil-pipe at each floor-level, providing for closets on each floor.

The foregoing detailed description has been given for clearness of understanding only, and no undue limitation is to be understood therefrom.

What I regard as new, and desire to secure by Letters Patent, is—

1. In closet-construction, the combination with a soil-pipe, of a plurality of closet-bowls grouped about said soil-pipe and connected therewith, and a plurality of compartment walls radiating from and supported on said soil-pipe, said soil-pipe extending upwardly above said compartment walls and serving to vent the closets.
2. In closet-construction, the combination of a soil-pipe fitting, comprising in integral formation, a central hollow body with a sloping lower wall and having a central upward pipe-section, and pipes formed integrally with and radiating from said hollow body and having upturned ends, a soil-pipe in the course of which said fitting is interposed, closet-bowls mounted on said upturned ends of said radiating pipes, compartment walls radiating from said soil-pipe, said soil-pipe extending above said compartment walls and serving to vent said closet-bowls, and tanks supported above and connected with said closet-bowls.
3. The combination with a soil-pipe, of a plurality of compartment walls radiating

therefrom, and means clampingly securing said compartment walls to said soil-pipe.

4. The combination with a soil-pipe, of a series of two-arm irons grouped about said pipe, and slabs interposed between adjacent arms of said irons and secured thereto.

5. The combination with a soil-pipe, of a plurality of compartment walls radiating therefrom, means securing said walls to said pipe, tanks located between said walls near said pipe, brackets connecting said tanks to said walls, and bowls located beneath said tanks and connected with said soil-pipe and with said tanks.

6. A soil-pipe fitting for the purpose set forth, comprising, in integral formation, a hollow circular body with a dished lower wall and central pipe-sections projecting from the upper and lower walls, and pipes formed integrally with and radiating from the circumference of said hollow body and provided with upturned ends equipped at their extremities with external flanges.

JAMES W. KELLY.
